UNITED STATES PATENT OFFICE.

LOUIS K. SYRSTAD, OF SHELTON, WASHINGTON.

COMBINATION SWIVEL AND BULL HOOK.

1,426,520.

Specification of Letters Patent. Patented Aug. 22, 1922.

Application filed February 1, 1922. Serial No. 533,436.

To all whom it may concern:

Be it known that LOUIS K. SYRSTAD, a citizen of the United States, and residing at Shelton, in the county of Mason and State 5 of Washington, has invented certain new and useful Improvements in Combination Swivels and Bull Hooks, of which the following is a specification.

This invention relates to improvements 10 in hooks and particularly to hooks used in logging and known as a combined swivel and bull hook.

An object of the invention is to provide 15 a swivel hook having a pivoted arm for preventing an element engaged in the hook from becoming accidentally disengaged and at the same time reinforcing the hook structure and equalizing the strain on the swivel portion.

20 Other objects and the details of construction are particularly pointed out in detail in the following description and claim.

In the drawings:—

Figure 1 is a side view of the hook.

25 Figure 2 is a side view taken at right angles to Figure 1.

Figure 3 is a sectional view taken on line 3—3 of Figure 1.

30 Figure 4 is a sectional view taken on line 4—4 of Figure 1.

The improved hook comprises a base portion 1 having the hook portion 2 formed integral therewith at one end and curved at the lower end as shown in Figure 1. The 35 base portion is formed with a bore 3, which receives the shank 4 of the swivel formed with an eye 5 and a head portion 6 for securing the swivel to the hook.

The free end of the base member 1 is bifurcated, as indicated at 7, one side being formed with a transverse opening 8 communicating with the bifurcation 7 and a depression 9 surrounds the opening 8, the purpose of which will presently appear.

45 An arm 10 is pivoted to the end of the hook at 11, the outer free end of which is formed with a head 12, so that the arm will fit in the bifurcated end of the base portion and the head 12 will extend above the base 50 and carry the strain on this side of the hook as will be obvious from Figure 1. The arm

10 is formed with a recess 13 adapted to receive a spring 14 which is secured at 15 to the arm and carries a button 16 on its free end adapted to project through the opening 18 in the arm into the opening 8 for holding the arm in closed position. The end portion of the base is formed with a longitudinal groove in the bifurcation as shown at 19 so that the button may be pressed into 60 the arm and the arm then moved outwardly into open position.

The depression 9 extends practically through the bifurcated arm as shown so that a person may use their finger for pressing 65 the button into the arm sufficiently that it can ride into the groove 19. This is clearly illustrated in Figure 4.

It will be noted that when the hook is in use the strain is evenly distributed through 70 both arms of the hook, that is the integral part 1 and the pivoted arm 10 to the base portion 1. This will prevent a twisting strain on the shank 4 and an excess strain 75 on one side of the head 6 which occurs in the ordinary hook. The head 12 carries all the pull transmitted through the arm 10 to the base portion, the button serving only to retain the arm in closed position in the bifurcated end of the base as shown. 80

What I claim is:—

A hook including a base portion, an eye swiveled in the base portion, a hook portion extending from the base portion and integral therewith at one end, the free end 85 of the base portion being bifurcated, an arm pivoted to the end of the hook portion and formed at its free end with a head, said arm fitting in the bifurcation in the base portion and the head thereon overlying substantially 90 the whole of the free end of the base, and a spring pressed latch carried by the arm for engagement in an opening in the end portion of the base for locking the arm in cooperative relation with the base. 95

In testimony whereof I affix my signature in the presence of two witnesses.

LOUIS K. SYRSTAD.

Witnesses:

ALDEN C. BAYLEY,
L. G. FREDSON.
